UNITED STATES PATENT OFFICE.

GEORGE W. MORDEN AND MARTIN WEBER, OF LOS ANGELES, CALIFORNIA.

BAG HOLDER.

Application filed January 9, 1925. Serial No. 1,409.

This invention has to do with a holder for paper bags, or the like, and it is an object of the invention to provide a simple, effective and practical device of this character.

5 The device provided by this invention is suitable for use in stores and other like places to hold paper bags, or the like, so that they are convenient for use.

An object of our invention is to provide a 10 device of the character specified which is simple and inexpensive of manufacture and neat and slighty in appearance.

A further object of our invention is to provide a device which will hold bags effectively 15 and securely and in a manner so that they can be readily removed as desired for use.

The various objects and features of our invention will be best and more fully understood from the following detailed description 20 of a typical preferred form of the invention throughout which description reference is had to the accompanying drawings in which—

Fig. 1 is a front elevation of the device provided by our invention.

Fig. 2 is a side elevation of the device.

Fig. 3 is a view showing the base portion of the device.

Fig. 4 is a detailed sectional view taken as 30 indicated by line 4—4 on Fig. 1 and

Fig. 5 is an enlarged transverse sectional view taken as indicated by line 5—5 on Fig. 1.

The device provided by this invention includes, generally, a base 10, an arm 11, detachably mounted on the base, and a pin 12 carried by the arm and base and adapted to hold paper bags, or the like.

The base 10 may be in the form of an elongate body or strip of metal preferably sheet 40 metal, and is adapted to be permanently mounted on a suitable support, say, for instance, a post or wall. To facilitate mounting of the base we prefer to provide it at suitable points, for instance, near its ends 45 with openings 14 suitable for receiving screws, or the like. The base may, in practice, be varied considerably in design and proportioning, it being preferred to construct it so that it is substantial and durable 50 and to design it so that it is neat and slighty in appearance.

The arm 11 is adapted to be mounted on the base 10 so that it has a part spaced a substantial distance from the base and adapted to hold one end of the pin 12. In the preferred 55 form of the invention the arm has one end,

which we will term the inner end, connected with the base and the other end, which we will term the outer end, spaced a substantial distance from the base and adapted to carry 60 one end of the pin. In accordance with our invention the inner end of the arm is adapted to be detachably connected with the base. The connection between the arm and base comprises an enlargement or head 15 provided on the inner end of the arm and suitable ears 16 provided on the body to receive 65 and hold the head. In the preferred form of construction the head 15 is tapered or wedge shaped and the ears 16, which are formed at 70 opposite edges of the base, are correspondingly tapered so that the head can be forced or wedged tightly into or between the ears. The ears 16 are in the form of tabs provided on opposite side edges of the base and are 75 turned in the manner clearly illustrated in Fig. 5 of the drawings so that they have flange parts 18 which hold the head 15 to the base in the manner illustrated throughout the drawings. The ears 16 are located at one 80 end of the base preferably at the upper end thereof, and the parts are arranged and related so that the arm when held by the ears extends toward the other end of the base so that its outer end is spaced from the lower 85 end portion of the base. The arm may be formed of a strip of sheet metal suitably shaped and proportioned as illustrated throughout the drawings. The arm adjacent the enlargement or head 15 is sufficiently 90 narrow to be passed between the flange parts 18 of the ears to facilitate connecting and disconnecting the arm and base when the head is moved upwardly out of position between the ears. 95

The pin 12 which is preferably in the form of a round bar or heavy wire, may, in practice be in the form of a nail having an elongate body 20 provided with a point 21 at one end and a head 22 at the other end. In the particular form of the invention illustrated in the drawings the pin 12 is fixed or secured to the outer end of the arm and is detachable from the base. In the drawings we have shown the outer end of the arm having a part 23 folded or bent back and have shown the body of the rail or pin passed through said folded part 23 so that it projects inwardly from the arm toward the base while the head 22 of the pin is confined between the folded part 23 and the main part of the arm as clearly illustrated in Figs. 2 and 4 of the drawings. The body 20 100 105 110

of the pin extends inwardly from the outer part of the arm to the base where the point 21 engages or is held by a suitable part of the base. In the preferred form of construction 5 the base is provided with an opening 30 to receive and hold the pointed portion of the pin. The opening 30 is preferably in the form of a tapered depression or socket extending longitudinally of the base to allow for movement 10 of the arm and pin relative to the base as the arm is being applied to or removed from the base. The socket 30 is proportioned so that the pin is supported by its lower end when the parts are in operating position as illustrated 15 through the drawings. By this arrangement the pin has its outer end supported by the outer end of the arm and its inner end supported by the base. It is preferred in practice to relate the parts, for instance, 20 to shape and proportion the arm 11 and socket 30 so that the arm is flexed somewhat when in operating position as illustrated in Figs. 1 and 2 of the drawings so that its outer end tends to move toward the base 25 and thereby effectively holds the pin in proper engagement with the base.

In using the device the arm 11 is removed from the base by moving it upwardly to disengage the head 15 from the ears 16. The pin 30 12 is then passed through a plurality of bags or the like, which are to be held by the device so that the bags are carried on the pin. The arm is then reapplied to the base by sliding the head 15 downwardly into position where

it wedges between the ears. The application 35 of the arm to the base causes the pin to enter and be held by the opening 30 in the base so that the bags are held on the pin between the outer end of the arm and the base. As the bags are required for use they may be torn 40 from the pin.

Having described only a typical preferred form of our invention we do not wish to limit ourselves to the specific details hereinabove set forth, but wish to reserve to ourselves any 45 changes or variations that may appear to those skilled in the art or fall within the scope of the following claim.

Having described our invention, we claim:

A bag holder comprising a base, an arm 50 having one end adapted to be connected to the base and the other end to be spaced from the base, means for attachably connecting the arm and base including a wedge shaped head 55 on the arm and ears on the base to receive and hold the head, a socket in the base, and a pin permanently carried by the end of the arm spaced from the base to extend from the arm into the socket in the base, the pin being in the form of a nail, the head of the nail being 60 permanently connected to the arm and the point of the nail extending into the base.

In witness that we claim the foregoing we have hereunto subscribed our names this 24th day of December, 1924.

GEORGE W. MORDEN.
MARTIN WEBER.
